(57) **CLAIM**

The ornamental design for a flexible feed sock, as shown and described.

DESCRIPTION

FIG. 1 is a top plan view of a blank from which the flexible feed sock is formed;

FIG. 2 is a front perspective view of the blank formed into the flexible feed sock;

FIG. 3 is a top plan view thereof;

FIG. 4 is a bottom plan view thereof;

FIG. 5 is a front elevation view thereof;

FIG. 6 is a left side elevation view thereof;

FIG. 7 is a rear elevation view thereof; and,

FIG. 8 is a right side elevation view.

The broken line showing of the flexible feed sock is included for the purpose of illustrating support hoops and forms no part of the claimed design.
